UNITED STATES PATENT OFFICE.

VICTOR D. RENWICK, OF CAMDEN, NEW JERSEY.

DETECTOR.

Application filed October 16, 1924. Serial No. 743,990.

This invention relates to new and useful improvements in detectors of the type particularly adapted for use in rectifying electric current oscillations, such as those received by wireless apparatus.

In the use of detectors of the so-called crystal or galena type, it is the common practice to employ a cat whisker for forming an electric connection with the sensitive spot or spots of the crystal or galena. This cat whisker is usually manually adjustable to enable the sensitive spots to be located and to vary the degree of pressure at which the cat whisker engages such spots. It is often times a very tedious proposition to locate a good sensitive spot and after one is located, the pressure of engagement is very often much too great or too little and the best results are not obtained.

It is the primary object of this invention to provide a detector of the above mentioned type which will establish connections between a cat whisker and a plurality of sensitive spots simultaneously, and which will automatically provide the proper degree of pressure for such connections, when properly mounted upon a support.

A further object of the invention is to provide means for manually establishing connections between the cat whisker and new or undamaged sensitive spots without losing the proper degree of pressure above referred to.

A still further object of the invention is to employ gravitational forces for establishing the above referred to proper degree of pressure for the connections with the sensitive spots of a crystal or galena.

Other objects and advantages of the invention will be apparent during the course of the following description.

In the accompanying drawing forming a part of this specification, and in which like numerals are employed to designate like parts throughout the same, the figure shows a central vertical sectional view of the detector embodying this invention and further shows the same properly mounted upon a support, such as a panel forming part of a wireless receiving set.

In the drawing, wherein for the purpose of illustration is shown a preferred embodiment of this invention, the numeral 5 designates a supporting element which is preferably formed of insulating material, such as

a panel in a wireless receiving set. This support 5 is provided with a pair of vertically aligned apertures 6 thru which the binding screws 7 project. These binding screws are employed for securing the resilient bracket mountings 8 to the support 5 and are for connecting conductors, such as electric wires, to said bracket mountings 8, the conductors being connected to the binding screws 7 by means of the outer nuts 65 9, the inner nuts 10 being employed for drawing the heads of the binding screws 7 against the apertured inner end portions of the bracket mountings 8 for securing them to the support 5.

The detector proper includes a piece of material 11 which is sensitive to oscillating currents and is adapted to rectify the same, the said piece of material 11 being properly termed a crystal or galena. This crystal or galena 11 is suitably molded in a soft metal container 12 adapted to be mounted within the crystal supporting cup 13. This cup is provided with a laterally projecting annular flange 14 at its upper open end and an integral depending nipple 15 of substantially conical formation, this nipple 15 being arranged to form part of the bottom wall of the cup 13. A bell-shaped casing 16 is telescopically connected with the cup 13 and is insulated therefrom by the ring 17. This ring engages the annular outwardly projecting flange 14 formed on the cup 13 and is retained in engagement therewith by the spun-over edge 18 of the bell-shaped casing 16.

The bell-shaped casing 16 is provided with an aperture 19 in its upper end within which is positioned the combination bearing and connector element 20. This connector 20 is secured to the bell-shaped casing 16 by means of the enlarged head portion 21 which bears against the outer face of the end of the casing 16, and the sleeve 22 shrunk or sweated on the depending cylindrical portion 23 of the element 20.

The element 20 is made use of as a connector by providing an annular groove 24 in the enlarged head portion 21, the groove 24 being adapted for receiving the furcations 25 of the upper resilient mounting bracket 8. The furcations 26 of the lower mounting bracket 8 are adapted for receiving therebetween the depending conical nipple 15 carried by the crystal or galena 110

supporting cup 13. It will now be seen that a quick detachable connection is provided between the mounting brackets 8 and the detector structure, the detector structure 5 being connected to the brackets by first passing the groove portion 24 of the enlarged head 21 between the furcations 25 after which the detector structure is fulcrumed upon the upper mounting bracket 8 10 for forcing the depending conical nipple 15 between the furcations 26 of the lower mounting bracket 8.

A washer 27, formed of cork, rubber, or other suitable insulating material, is adhesively secured to the upper face of the soft metal container 12 and is positioned with its centrally located opening 28 arranged in alinement with the crystal or galena 11 for exposing a suitable amount of the sensitive 20 surface 11^a of the same. It will be seen that the lower flanged end 22^a of the sleeve 22 and the lower end of the cylindrical portion 23 of the element 20 bear against the outer face of the insulating washer 27. The 25 bore of the cylindrical portion 23 and the opening 28 in the washer 27 form a chamber communicating with the sensitive surface 11^a of the crystal or galena 11. This chamber 29 is employed for confining or housing loose granules of conductive material 30 so that the same will gravitate toward the sensitive surface 11^a of the crystal or galena 11 and will engage the same.

Journalled in the bearing portion or bore 35 of the element 20 is a hollow shaft 31 having a laterally projecting annular flange 32 formed at its lower end, as illustrated.

The upper end of this shaft 30 is reduced and squared, as at 33 for receiving the metallic bushing 34 molded in the operating knob 35, the said knob 35 with its bushing 34 being detachably secured to the reduced squared portion 33 by the nut 36. For the purpose of maintaining the annular flange 45 portion 32 of the shaft 31 in engagement with the upper wall of the granular confining chamber 29, a spring 37 is interposed between the upper surface of the enlarged head 21 and the inner end of the bushing 34.

Extending axially thru the bore of the hollow shaft 31 and suitably secured to the inner end thereof, as by the solder 38, are the loops of conductor wire 39 which depend from the lower end of the shaft 31 and project into the mass of loose granules 30. These wire loops 39 will be termed the cat whisker of the detector.

The operation of the detector embodying this invention may be described as follows:-

It is very important to note that this detector structure is properly mounted upon a support or panel when its axis extends vertically or substantially vertically. This is due to the fact that I desire to make use 65 of gravitational forces for establishing the

proper degree of pressure engagement between the granules 30 and the sensitive surface 11^a of the crystal or galena 11. By properly selecting the granules 30, as to their size, and causing them to gravitate toward the sensitive surface 11^a, I can establish the proper degree of pressure connection between the cat whisker 39 and the sensitive spots of the said crystal or galena 11. The mass of loose granules of conductive 75 material 30 may be agitated or stirred for causing the same to seek new sensitive spots on the surface 11^a by rotating the shaft 31 within the bearing 21, the said shaft being rotated by means of the operating knob 35. 80

The circuit thru this detector may be described as extending from the upper binding screw 7 thru its respective bracket mounting 8 to the element 20 from which is passes thru the shaft 31 to the cat 85 whisker 39. The lower ends of the cat whisker 39 are properly connected to a plurality of sensitive spots on the surface 11^a by the mass of granule conductive material 30. The crystal or galena 11 is connected to its supporting cup 13 by means of its soft metal container 12 while the cup 13, thru its depending conical nipple 15 is connected to the lower mounting bracket 8 which in turn is connected to the lower 95 binding screw 7.

It is to be understood that the form of this invention herewith shown and described is to be taken as a preferred example of the same, and that various changes in the shape, 100 size, and arrangement of parts may be resorted to without departing from the spirit of the invention or the scope of the subjoined claims.

Having thus described the invention, I 105 claim:-

1. A detector of the type described comprising an oscillating current rectifying mass, a granular conductor contacting with said mass, and current conducting means engaging the granular conductor and movable in respect to the rectifying mass to agitate the granules with respect to said mass.

2. A detector of the type described comprising a piece of material sensitive to oscillating currents and adapted to rectify them, a finely divided conductor gravitating toward and contacting with said piece of material, and a second conductor projecting into said finely divided conductor 110 and movable for agitating the same.

3. A detector of the type described comprising a piece of material sensitive to oscillating currents and adapted to rectify them, a finely divided conductor contacting with said piece of material, a second conductor projecting into said finely divided conductor and movable in respect to the piece of material to stir the particles of the divided conductor, and means for confining 125 130

the activity of the finely divided conductor to the said piece of sensitive material and the second conductor.

4. A detector of the type described comprising a cup, a piece of material sensitive to oscillating currents and adapted to rectify them positioned in said cup, a casing enclosing said cup, a finely divided conductor gravitating toward and contacting with said piece of material, and a second conductor carried by and movable in respect to the casing and entering said finely divided conductor for agitating the latter.

5. A detector of the type described comprising a cup, a piece of material sensitive to oscillating currents and adapted to rectify them positioned in said cup, a casing enclosing said cup, a finely divided conductor gravitating toward and contacting with said piece of material, and a second conductor projecting into said finely divided conductor and movable for agitating the same.

6. A detector of the type described comprising a cup formed of conductive material, a piece of material sensitive to oscillating currents and adapted to rectify them positioned in said cup, a casing formed of conductive material telescopically associated with said cup and insulated therefrom, a conductor movably carried by the casing and depending toward said piece of material, a finely divided conductor gravitating toward said piece of material and conductively connecting the first mentioned conductor thereto, and means for moving the conductor carried by the casing for agitating the finely divided conductor.

7. A detector of the type described comprising a cup formed of conductive material, a piece of material sensitive to oscillating currents and adapted to rectify them positioned in said cup, a casing formed of conductive material telescopically associated with said cup and insulated therefrom, a conductor movably carried by the casing and depending toward said piece of material, a finely divided conductor

gravitating toward said piece of material and conductively connecting the first mentioned conductor thereto, means for moving the conductor carried by the casing for agitating the finely divided conductor, and means for confining the activity of the finely divided conductor to said piece of sensitive material and the conductor carried by the casing.

8. A detector of the type described comprising a cup, a piece of material sensitive to oscillating currents and adapted to rectify them positioned in said cup, a bell-shaped casing positioned over said cup and insulated therefrom, a cylinder having an open lower end mounted within said casing and axially alined with the piece of sensitive material, an insulating washer concentric with said cylinder interposed between the lower open end of the latter and the piece of sensitive material, a mass of finely divided conductive material positioned within the bore of the cylinder and the washer and gravitating against said piece of sensitive material, and a wire conductor projecting into the finely divided material.

9. In a device of the type described, the combination with a support, a pair of laterally alined terminals passing therethrough, and an angle, resilient bracket mounted on the support by each terminal, said brackets including parallel portions projecting from said support and having their ends bifurcated, of a detector unit quickly detachably connected to said bracket projections, said unit including a casing, a connector element projecting from one end and having an annular groove formed therein for receiving the furcations of one bracket, and a connector element projecting from the remaining end of the casing, said last mentioned connector element being of conical formation and adapted to have its smaller end portion received between the furcations of the remaining bracket.

In testimony whereof I affix my signature.
VICTOR D. RENWICK.
